UNITED STATES PATENT OFFICE.

JOHN A. LELAND, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

BENCH-DRILL BRACE.

1,200,628.

Specification of Letters Patent.

Patented Oct. 10, 1916.

Application filed November 24, 1914. Serial No. 873,742.

To all whom it may concern:

Be it known that I, JOHN A. LELAND, a citizen of the United States, and resident of Montague, in the county of Franklin and State of Massachusetts, have invented certain new and useful Improvements in Bench-Drill Braces, of which the following is a specification.

This invention relates to appliances or tools for operating drills, the operation being effected by hand, such devices being commonly known as drill braces, the present invention relating to such tools or appliances that are intended to be secured to a bench or table in position for manual operation.

One of the objects of my invention is to provide an improved feed mechanism for automatically effecting the downward feed movement of the drill or other tool, the mechanism including means for varying the amount of feed of the tool in relationship to the number of its rotations.

A further object is to provide an implement of this character having improved changed speed mechanism to enable the tool to be operated at either one of a plurality of different speeds of rotation.

With these and further objects in view, my invention consists in the improvements which I shall now proceed to describe and claim.

Of the accompanying drawings: Figure 1 is a side elevation of a tool or implement constructed according to my invention, said figure omitting the lower portion of the frame and means for supporting or clamping the appliance in position for use; Fig. 2 is an elevation from the other side from that of Fig. 1, parts being broken out; Fig. 3 represents a section on line 3—3 of Fig. 1, on a larger scale; Fig. 4 is a perspective view of the different parts of the coupling shown in Fig. 3, said parts being separated from each other; Fig. 5 represents a section on line 5—5 of Fig. 1, on a larger scale; Fig. 6 is a view similar to Fig. 5, but illustrating a different position of the bolts or dogs used for changing the speed of the gearing; Fig. 7 represents a section on line 7—7 of Fig. 5; Fig. 8 is a perspective view of one of the pinions shown in Fig. 5, it being understood that the other pinion is similarly formed; Fig. 9 is a perspective view of the two sleeves employed for effecting a change of speed; Fig. 10 is a perspective view of the

clutch hub of the change speed gearing, the bolts or dogs being included in said figure but removed from their position of use; Fig. 11 represents a section on line 11—11 of Fig. 2, on a larger scale; Fig. 12 is a view similar to a portion of Fig. 11, showing a different position of the pawl which actuates the feed screw; Fig. 13 is a perspective view of the different parts, separated, which comprise the means for varying the operation of the pawl which actuates the feed screw; Fig. 14 represents a section on line 14—14 of Fig. 11; Fig. 15 represents a section on line 15—15 of Fig. 2, on a larger scale, said figure showing also a portion of the cam carried by one of the gears.

Similar reference characters represent similar parts in all of the views.

A frame 20, having suitable means not illustrated for securing it to a bench or elsewhere for use, has its upper portion formed to provide three bearings 21, 22, 23, in alinement with each other, a spanning portion 24 providing for the support of a stud or shaft 25 (see Figs. 1 and 2). These parts may be all of a single casting.

Mounted on or rotating with the stud 25 is a compound gear having an inner series of gear teeth 26 and an outer series of gear teeth 27. A crank 28 having a suitable handle is connected in any preferred manner to enable the compound gear to be manually rotated.

Mounted in the bearings 21, 22, is a tool spindle 29 having a chuck 30 for holding the drill or other tool.

Loosely mounted on the spindle 29 are two pinions 31, 32, meshing respectively with the gear teeth 26, 27, of the compound gear. Referring to Figs. 5 to 8 inclusive, it will be seen that the pinions 31 and 32, are provided with cylindrical shoulders 33, the same being bisected by slots or recesses 34 adapted to receive the bolts or dogs presently described. A clutch hub 35 is directly mounted upon the spindle 29 and is secured thereto by a spline 36 entering a groove 37 in the spindle. This provides for a direct connection between the hub and the spindle, although the spindle is adapted to be moved or adjusted longitudinally, as hereinafter described.

As best shown in Fig. 10, the clutch hub is provided with a longitudinal socket 38 in which are mounted two bolts or dogs 110

39, 40, a spring 41 (see also Figs. 5 and 6) being located between the two dogs so as to project either one of them, when permitted, into engagement with a recess 34 of one of the two pinions.

In order to selectively control the two dogs for the purpose of rendering either one of the pinions 31, 32, operative, the said dogs are provided with pins 42 which 10 project into slots formed in one side of a sleeve 43 which is mounted to rotate about the clutch hub 35. The ends of this sleeve 43 surround the cylindrical shoulders 33 of the two pinions. The slots in the sleeve 43 are formed with cam walls 44, 45 (Fig. 9). Mounted upon the inner sleeve 43 is an outer sleeve 46 connected to the inner sleeve by suitable means such as a lug 47 and recess 48, so that when the outer sleeve 20 46, the outer surface of which is preferably milled or roughened, is rotated, it will insure corresponding rotation of the inner sleeve 43 so that the cam edges 44, 45, of the slots in the inner sleeve, will control which 25 of the bolts or dogs 39, 40, shall be projected. This is clearly illustrated by comparing Figs. 5 and 6. In Fig. 5 a dog 39 is engaged with the pinion 31 and therefore said pinion 31 is locked to the spindle 29 while the other pinion 32 is left idle. Since the pinion 31 meshes with the gear teeth 26 of the compound gear, rotation of the latter by means of the crank will 30 impart to the spindle its lesser speed of rotation. By rotating the sleeves so that the dog 39 is withdrawn and the dog 40 is permitted to be projected by the spring 41, the said dog 40 will interlock with the pinion 32, the pinion 31 at the same time 35 being left idle. Operation of the compound gear then imparts the higher speed of rotation to the spindle because the pinion 32 meshes with the outer larger series of gear teeth 27. The movements just described 40 are supposed to mean movements of the dogs to their extreme inner or outer positions. If the sleeve 43 is moved only to an intermediate position so that the pins 45 of the dogs bear against about the mid-lengths of the cam walls 44, 45, then both of the dogs will project sufficiently so that both of the pinions 31, 32, are locked to the clutch hub, thus locking the spindle so that the clutch can be conveniently opened and 50 closed for the substitution of tools. This locking of the spindle is due to the fact that if both pinions 31, 32, are locked to the spindle through the medium of the clutch hub and its bolts or dogs, the engagement of the two gears 26, 27, with the two pinions, will necessarily effect this locking because of the different sizes of the said two gears 26, 27.

The vertical aperture in the upper bearing 23 is internally threaded (see Fig. 14),

the upper portion of the bearing being enlarged to form a recess for the ratchet ring 60 hereinafter described. Fitting said screw threads is the feed screw 49, which is preferably provided with a handle 50 at its 70 upper end to enable it to be adjusted manually when desired. This feed screw is coupled to the tool spindle 29 by means of a construction best illustrated in Figs. 3 and 4. These figures are drawn horizontally, 75 but it will be understood of course that in practice the implement is usually employed while the spindle is in vertical position, although such position of course is not always necessary. The inner end of the 80 feed screw 49 is reduced as at 51, this portion entering a socket 52 in the end of the spindle 29. This reduced portion is formed or provided with an annular groove 53. One side of the socket 52 is slotted as at 54, 85 a key piece 55 being located in said slot and engaging the annular groove 53. The key piece is held in place by a split spring sleeve 56.

It will now be understood that the tool 90 spindle 29 can be freely rotated at any speed by the gearing described, although the feed screw 49 is only rotated intermittently as herein described. Preferably a ball bearing is provided between the tool 95 spindle and the feed screw, the same being illustrated as comprising balls 57 between two bearing rings 58, 59.

As illustrated by comparing Figs. 3 and 4 with Fig. 1, the tool spindle and feed screw 100 may be readily connected by the coupling, or disconnected, because of the coupling being accessible in the space between the frame bearings 22, 23. Assembling of the parts, or separating them for such purposes as 105 cleaning, is easily effected. By simply springing the sleeve 56 open, and removing the key piece 53, the coupling is separated, and the tool spindle can then be slipped out of the bearings 21, 22, and out of the change- 110 speed gearing, and the feed screw can be then removed from the threaded bearing 23 by rotating it.

Mounted in the recess at the upper end of the bearing 23 is a ratchet ring 60 (Figs. 11, 115 12 and 14), said ring being held in said recess so that it can have no vertical movement, by a strip 61 held by suitable means such as one or more screws 62 (Figs. 1 and 2). The ratchet ring is connected to the 120 feed screw by means of a spline 63 carried by the former entering a vertical groove 64 in the latter. This prevents the feed screw from having any movement except when the ratchet ring is rotated. The ratchet ring 125 is actuated by a pawl carried by a slide 65 (Figs. 2, 11, 12 and 14), said slide having at one end a hollow stud 66 the outer end of which is provided with a transverse groove 67 (Fig. 13). A pin 68 is mounted 130

in the hollow stud 66 and has a head 69 at its inner end, which takes a bearing against the inner wall of the said stud. Projecting from the inner face of the head 69, at one side of the center thereof, is a rib 70 which constitutes the pawl for actuating the ratchet ring. Secured to the end of the pin 68 which projects from the stud 66 is a knob or button 71 preferably having a milled periphery. Said knob is provided with two lugs 72 adapted to engage the groove 67. It is to be understood that the stud 66 having the groove 67 is fixed so that it cannot rotate. A spring 73 tends to normally hold the pin 68 with the pawl in engagement with the teeth of the ratchet ring.

Explaining at this point that by the mechanism hereinafter described the pawl slide 65 is always given a certain amount of reciprocation, it will be understood that when the pin 68 is so turned that the pawl 70 occupies the position shown in Fig. 11, the pawl will impart as much movement to the ratchet ring as is possessed by the slide 65. This is supposed to actuate the feed screw at its maximum speed of advance or downward movement during work. If a slower advance of the feed screw is desired, the user withdraws the pin 68 slightly against the action of the pin 73, by means of the knob 71, and then gives the pin a one-half turn, then permitting the lug 72 to return again into the groove 67. This turns the pin so that the pawl 70 is at the other side of the center of rotative adjustment of the pin, as shown by Fig. 12, so that thereafter, when the before-mentioned uniform extent of movement is imparted to the slide 65, the ratchet ring will not be actuated so far, a considerable amount of movement of the pawl being then simply lost motion. This structure provides for a quick change from high to low feed, and vice versa.

If the knob 71 be given less than the half-turn above described, and then released, the lugs 72 cannot enter the groove 67, and consequently the pawl 70 is held out of engagement with the ratchet, thus leaving the feed screw free to be rapidly rotated by means of its handle 50.

To automatically reciprocate the pawl slide 65 so that the feed screw will be intimately actuated whenever the appliance is in use, I provide an elbow lever having arms 74, 75 (see Figs. 1 and 2). Said lever is pivoted to the frame at 76. The tip 77 of the arm 74 is rounded and carries a pin or screw 78 (Fig. 11), said pin entering a recess 79 in the upper portion of the frame. A spring 80 confined between the inner end of the said recess and the pin 78 acts to cause the arm 74 of the elbow lever to normally hold the pawl slide retracted. The connection is such that all movements of the elbow lever are imparted to the pawl slide. The

end of the arm 75 of the elbow lever is provided with a pin 81 (Fig. 15) on which is mounted a roll 82, said roll engaging an inner eccentric face 83 carried by the compound gear, said eccentric face constituting a cam so that each rotation of the compound gear by means of the crank causes one complete oscillation of the elbow lever and consequently causes one complete reciprocation of the pawl slide so that the pawl will give one step movement to the ratchet ring 60, and thus cause the feed screw to advance the tool spindle and carry the tool slightly farther into the work.

Owing to the coupling between the ends 80 of tool spindle 29 and feed screw 49, the tool can be quickly raised without imparting any rotation to it. This is done by turning the feed screw by means of its handle 50, the pawl 70 being held out of the way of the teeth of the ratchet ring by means of its knob 71.

Having described my invention, I claim:

1. An implement of the character described, comprising a frame having bearings, a tool spindle rotatably and longitudinally movable in said bearings, gearing for rotating the spindle, a feed screw coupled to said spindle, a ratchet ring having a splined connection with the feed screw, a slide mounted in the frame, a pawl carried by the slide for actuating said ratchet ring, and means for automatically reciprocating the slide when the tool spindle is rotated.

2. An implement of the character described, comprising a frame having bearings, a tool spindle rotatably and longitudinally movable in said bearings, gearing for rotating the spindle, a feed screw coupled to said spindle, a ratchet ring having a splined connection with the feed screw, a slide mounted in the frame, a pawl carried by the slide for actuating said ratchet ring, and means for automatically reciprocating the slide when the tool spindle is rotated, said means comprising an elbow lever pivoted to the frame and engaging the slide, and a cam for actuating said lever.

3. An implement of the character described, comprising a frame having bearings, a tool spindle rotatably and longitudinally movable in said bearings, gearing for rotating the spindle, a feed screw coupled to said spindle, a ratchet ring having a splined connection with the feed screw, a slide mounted in the frame, a hollow stud carried by the slide, a pawl adjustably mounted in the stud and engaging said ratchet ring, and means for automatically reciprocating the slide when the tool spindle is rotated.

4. An implement of the character described, comprising a frame having bearings, a tool spindle rotatably and longitudinally movable in said bearings, gearing

- for rotating the spindle, a feed screw coupled to said spindle, a ratchet ring having a splined connection with the feed screw, a slide mounted in the frame, a hollow stud 5 carried by the slide, a pawl adjustably mounted in the stud and engaging said ratchet ring, means being provided for setting and holding the pawl out of engagement with the ratchet ring, and means for 10 automatically reciprocating the slide when the tool spindle is rotated.
- 15 5. An implement of the character described, comprising a frame having bearings, a tool spindle rotatably and longitudinally movable in said bearings, gearing for rotating the spindle, a feed screw coupled to said spindle, a ratchet ring having a splined connection with the feed screw, a slide 20 mounted in the frame, a hollow stud carried by the slide and having a transverse groove in its outer ends, a pin mounted in said stud and having a rib at its inner end to engage the ratchet ring, a spring to press said pin inwardly, a knob secured to the 25 outer end of the pin and having a lug to engage the groove of the stud, and means for automatically reciprocating the slide when the tool spindle is rotated.
- 20 6. An implement of the character described, having a frame provided with bearings, a tool spindle rotatably and longitudinally movable in said bearings, gearing for

rotating it, a feed screw coupled to said spindle, a ratchet ring having a splined connection with the screw, a slide, a spring-pressed pin carried by said slide and engaging said ratchet ring, means for automatically operating the pin when the tool spindle is rotated, and means for varying the action of said pin to change the speed of longitudinal movement of the tool spindle.

7. An implement of the character described, comprising a frame having bearings, a tool spindle rotatably and longitudinally movable in said bearings, gearing for 45 rotating the spindle, a feed screw coupled to said spindle, a ratchet ring having a splined connection with the feed screw, a slide mounted in the frame, a pawl carried by the slide for actuating said ratchet ring, 50 the frame having a recess behind the slide, the slide having a pin projecting into said recess, a spring in the recess acting on the pin of the slide to move the latter in one direction, an elbow lever engaging the slide, 55 and a cam carried by the spindle-rotating gearing for actuating the lever to move the slide in the other direction.

In testimony whereof I have affixed my signature, in the presence of two witnesses. 60
